DESCRIPTION

U.S. PATENT DOCUMENTS

FIG. 1 is a perspective view of a combined television and base showing my new design;

D357,912 S * 5/1995 Martin D14/374
D364,395 S * 11/1995 Uratani D14/374
5,582,373 A * 12/1996 Baudot 248/917
D412,891 S 8/1999 Sumii
D416,876 S * 11/1999 Yin D14/126
D424,068 S * 5/2000 Takemasa D14/126
D424,538 S * 5/2000 Hayashi D20/10
D432,103 S * 10/2000 Mitsuhashi D14/126
D438,848 S * 3/2001 Kita D14/126
D441,732 S 5/2001 Ota

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIG. 8 is a perspective view of a second embodiment of a
combined television and base, wherein the panel portion of
the base has reflecting surfaces; and,

FIG. 9 is a front elevational view thereof. The rest of views
thereof is the same as those of the embodiment of FIG. 1.
